DISPENSING CABINET

Filed Aug. 18, 1925

UNITED STATES PATENT OFFICE.

HOWARD PARKER, OF BERLIN, NEW HAMPSHIRE, ASSIGNOR TO BROWN COMPANY,
OF BERLIN, NEW HAMPSHIRE, A CORPORATION OF MAINE.

DISPENSING CABINET.

Application filed August 18, 1925. Serial No. 50,941.

This invention relates to dispensing or sheet delivery cabinets, and more particularly to those from which interfolded sheets, such as paper towels, may be consecutively removed.

Such towels are usually purposed in packet form, ready for insertion in a dispensing cabinet. To permit their successive removal therefrom, the towels are usually folded back and forth several times, the last fold of each towel being in overlapping engagement with the first fold of the adjacent towel in the packet, so that when one towel is withdrawn through the exit slot in the cabinet, the end 10 of the adjacent towel emerges therethrough so that it may be grasped for withdrawal. Heretofore, such cabinets have found application in the wash rooms of large buildings and hotels, but have not been used extensively 15 for household or similar purposes.

The primary object of the present invention is to provide an attractive and durable cabinet, of simple and inexpensive construction, which will be suitable for extensive use 20 and which possesses certain features of construction which render it efficacious and dependable in operation.

One feature of the present invention relates to construction by which the sheets may 25 be removed from the front end of the cabinet, the successive sheets being directed toward the emerging slot of the cabinet by suitable guides provided therein. Another feature of the invention relates to a construction which 30 permits the cabinet to be opened for replenishment of the towel supply or for other purposes, and means tending to close the cabinet when it is open, so that the towels are not liable to accidental disengagement or permitted to fall out of the cabinet after they are 35 once inserted. A further feature of construction relates to means which forces or feeds the towels forwardly to the exit slot at the front of the cabinet. With these and other 40 features in view, the invention consists in the construction, combination and arrangement of parts hereinafter more fully described in conjunction with the accompanying drawings, in which

Figure 1 shows in perspective view the

cabinet of the present invention with the cabinet fully opened and swung away from its support.

Figure 2 represents a longitudinal section on the line 2—2 of Figure 1.

Figure 3 represents a transverse section on the line 3—3 of Figure 1, and shows the cabinet "loaded" with towels.

Referring to the drawings, the cabinet as shown comprises an open back receptacle for 60 housing or containing a supply of interleaved towels as indicated in general at A, hingedly or swingably mounted on a back or cover B. The cabinet is preferably constructed of sheet metal, and the receptacle A may be 65 formed by pressing a properly cut blank by suitable dies. Or it may consist of several pieces which have been suitably fastened together, as by spot welding, or of an integral piece properly cut and bent to form, with its 70 abutting edge portions suitably fastened together.

The receptacle, as shown, is of substantially rectangular or box form, and may have stamped, raised portions D in the form of 75 rectangular panels on its sides, or any other design for the purpose of ornamentation, as well as to make the cabinet strong and stiff. The towels T are inserted through the open back of the receptacle, and are supported by 80 the bottom 1 in a standing or upright position, the towels facing the front 2 of the receptacle. The front 2 is provided with a central horizontal elongated opening or slot 3, of proper dimensions to allow the removal 85 of the towels, and through which the end of the foremost towel T projects so that it may be grasped and withdrawn. The edges of the front defining the slot are rolled inwardly in the form of beads 4, 4, so as to present a finished exterior appearance to the cabinet, and to prevent excessive frictional resistance to the towels as they are withdrawn from the receptacle.

To present the towels in alinement with 95 each other and in proper position for emergence through the exit slot so that they will not become creased in the cabinet or torn in withdrawal therefrom, within the receptacle A and welded or otherwise suitably secured 100

to the ends 5 and 6, respectively, are the inclined plates or leaves 7 and 7', converging toward the exit slot 2. These plates act as guides to properly direct the towels toward the exit slot, so that upon inserting a packet of towels into the cabinet, no particular attention need be paid to their perfect arrangement or positioning. The guides also tend to hold back the rear towels sufficiently to permit ready withdrawal of the first towel, without, however, interfering with their normal progress or feed towards the exit opening, which is effected by means hereinafter described.

15 The receptacle A is supported in a manner to permit the cabinet to be opened at will for replenishment of the towel supply, and then automatically closed. To this end, the receptacle is provided at its end 6 with tubular 20 knuckles for butt hinge members 8 and 9. These members are rotatably mounted on a pintle 10, secured to a pair of spaced tubular knuckles 12 and 13 at an edge of the back or cover B, so that the receptacle A may be 25 swung forward and its open back made accessible for the insertion of a fresh towel supply thereto. Between the knuckles 12 and 13 is located a torsion coil spring 15, one end 30 16 of which engages the outer face of the end 6 of the receptacle, and the other end 17 extends in the rear of the back B, so that upon opening the cabinet the spring 15 is tensioned and forces the receptacle back to its closed position when it is left freely open.

35 To ensure a feeding or forward progression of the towels towards the exit slot, on the back B is hingedly mounted, near both its ends, a pair of spring hinged leaves 20, 21. Each leaf is provided at its inner edge 40 with spaced abutment hinge elements 22 and 23. Similarly, tongues are punched from the back of the receptacle and rolled in the form of spaced complementary hinge elements 24 and 25. A pintle 26, secured to the elements 24 and 25, passes through the several hinge elements. The spring biasing action of each leaf against the towels is effected by a coil or torsion spring 27, wound around the pintle 26 between the hinge elements 24 and 25, one 50 end 28 of the spring engaging the outer face 21 of the leaf, and the other end 29 engaging the rear face of the back. The spring thus tends to force the leaf against the towels when the cabinet is closed and to feed them forwardly toward the front 2 as those in front are withdrawn. The edge portion 30 of the leaf, contacting with the last towel, is preferably rounded or curved somewhat, so as not to cut into or become embedded therein. Before passing, it may be stated that the spring 15, which tends to automatically close the receptacle against the back, is sufficiently powerful to overcome the action of the small springs 27 and to close the cabinet.

65 For the purpose of locking the receptacle

to the back, at the edge of the back B is provided a locking member, consisting of a resilient metal strip having a protuberance or catch 35 constructed to engage in a mating indent or hole 36 of the receptacle A for 70 maintaining the cabinet locked to the supporting structure. The outer end of the strip has a thumb element 37 having a cam surface, by which the protuberance 35 may be disengaged from the indent 36 to allow the 75 cabinet to be swung forward from the structure 39 to which the back is secured. When the cabinet is automatically forced back to the structure by the spring 15, the end 5 engages the cam surface of the element 37, forcing the spring strip laterally and then releasing it in a manner to cause the protuberance 35 to become engaged in the indent 36, and thus locking the cabinet to the back. The back is preferably provided with a plurality 85 of apertures or holes 40 therethrough, so that the receptacle may be conveniently secured as by screws to a wall, door, or other suitable supporting structure indicated at 39.

80 In the cabinet of the present invention, the towels may be readily inserted within the receptacle without any particular attention to their proper alinement, and the plates direct them towards the exit slot 3 in proper position so that the end of the foremost towel 90 protrudes therethrough and may be grasped for removal. The leaves 20, 21 provide for a forward feeding of the towels, so that the cabinet may be depended upon to successively 95 present the towels to the front 2 for removal 100 from the receptacle. Moreover, automatic closing of the cabinet is provided, when it is swung open for the replenishment of the towel supply, so that the towels are not likely 105 to become accidentally disengaged from one 110 another, or to fall out of the cabinet.

115 It is to be noted that the entire cabinet is constructed of metal stampings, except for the small incidental parts such as the coil springs, so that they may be manufactured inexpensively and sold very cheaply. It is especially adapted for manufacture in small units, each to contain about 100 towels, and is particularly suitable for household or similar use.

Having thus described this invention, it is evident that various changes might be resorted to in form, construction and arrangement of the several parts, without departing from the spirit or scope of this invention. Hence I do not intend to limit myself to the construction herein set forth, but

120 What I claim is:

1. A dispensing cabinet comprising a back 125 for securement to a support, a receptacle for containing a supply of interleaved sheets hingedly secured thereto and having a horizontal slot at its front through which said sheets may be successively withdrawn, and a pair of inclined plates within said receptacle 130

and converging toward the ends of said slot for guiding said sheets towards said slot.

2. A dispensing cabinet comprising a back for securement to a support, a receptacle for housing a supply of interleaved sheets hingedly secured thereto and having a horizontal slot at its front through which said sheets may be successively withdrawn, means tending to close and lock said receptacle to said back when the cabinet is open, and a pair of inclined leaves within and adjacent to the ends of said receptacles and converging toward said slot for guiding the sheets in proper position thereto.

15 3. A dispensing cabinet comprising a back member for securement to a support, a receptacle for housing a supply of interleaved sheets hingedly secured at a side portion thereto, said receptacle having a horizontal 20 slot at its front through which said sheets may be successively withdrawn, a pair of inclined leaves within and adjacent to the ends of said receptacle and converging toward said slot, for guiding the sheets in proper 25 position thereto, means tending to close and lock said receptacle to said back when the

cabinet is open, and a pair of leaves spring hingedly secured at each end of said back and bearing against said sheets in a manner to tend to feed them toward said exit slot.

4. A dispensing cabinet comprising a back 30 member for securement to a support, a receptacle for housing a supply of interleaved sheets hingedly secured at a side portion thereto, said receptacle having a horizontal slot at its front through which said sheets 35 may be successively withdrawn, a spring engaging said back member and said receptacle and which becomes tensioned when swung open so as to force the receptacle back to its 40 closed position, a pair of inclined leaves within and adjacent to the ends of said receptacle and converging towards said slot for guiding the sheets in proper relation thereto, and a pair of leaves spring-hingedly secured at each end of said back and bearing against 45 said sheets so as to feed them towards said exit slot.

In testimony whereof I have affixed my signature.

HOWARD PARKER.
